UNITED STATES PATENT OFFICE.

HENRY R. EDGEcomb, OF WILKINSBURG, PENNSYLVANIA, ASSIGNOR TO WESTINGHOUSE ELECTRIC AND MANUFACTURING COMPANY, A CORPORATION OF PENNSYLVANIA.

GAGING-MACHINE.

1,274,698.

Specification of Letters Patent. Patented Aug. 6, 1918.

Application filed December 4, 1913. Serial No. 804,665.

To all whom it may concern:

Be it known that I, HENRY R. EDGEcomb, a citizen of the United States, and a resident of Wilkinsburg, in the county of Allegheny and State of Pennsylvania, have invented a new and useful Improvement in Gaging Machines, of which the following is a specification.

This invention relates to thickness gaging machines for sheet material, and is especially designed for use in gaging the built-up mica sheets employed in connection with the insulation of electrical machines.

As is well known, such mica sheets are built up by applying successive layers of pieces of mica and shellac or other binder until the proper thickness is obtained. Then the uniformity of thickness of the sheet is tested by optical or manual methods, and the thin places are further patched. The best known methods of testing and gaging are, however, extremely tedious, as very exact and painstaking work is required.

The object of the present invention is to provide a machine which will do automatically and rapidly the testing and gaging which are now laboriously done by hand.

Broadly, the invention contemplates a machine having power driven caliper feed rollers associated with automatic recording devices in the nature of scribes, so arranged as to produce marks upon a mica sheet, as it passes between the rollers, of such a nature as to indicate the exact location of those portions of the sheet which are too thick or too thin.

In order that the invention may be readily understood, reference is had to the accompanying drawings forming part of this specification, in which,

Figure 1 is a fragmentary front elevation of a machine constructed in accordance with my invention, parts being broken away;

Fig. 2 is a side elevation thereof, parts being in section substantially on the line 2—2 of Fig. 1, looking in the direction of the arrow;

Fig. 3 is a sectional plan substantially on the line 3—3 of Fig. 1;

Fig. 4 is a complete front elevation of the machine on a reduced scale;

Fig. 5 is a sectional plan view taken substantially on the line 5—5 of Fig. 1;

Fig. 6 is a diagram showing the circuits employed; and,

Fig. 7 is a view showing the appearance of a sheet after it has passed through the machine.

Referring to the drawings in detail, the machine comprises a fixed outer frame 1, and a movable inner frame 2. The frame 2 is capable of sliding vertically in the frame 1, and may be adjusted relatively thereto by means of screws 3 and lock nuts 4.

Journaled in the lower part of the frame 1 is a power shaft 5, on the outer end of which is mounted a drive wheel 6, which, in the embodiment shown, is illustrated as capable of receiving a belt. On the shaft 5 are rigidly secured a series of rollers 7, spaced at any suitable distances apart. A second series of rollers 8 are disposed one immediately above each of the rollers 7, the arrangement being such that there are a plurality of pairs of rollers 7 and 8.

Each of the rollers 8 is mounted upon a stud carried by the short arm 9 of a bell crank lever pivoted at 11 to a lug 11^a, carried by the lower transverse member 2^c of the frame 2. The long arm 10 of each bell crank lever extends upwardly and terminates in an enlarged head 12, which projects between a pair of parallel transverse members 2^a and 2^b, forming part of the frame 2.

In the enlarged head 12 of each bell crank lever are set two groups of contact screws 13 and 14, four of such screws being shown in each group. Any desired number may, however, be employed. The contact screws 13 and 14 are adapted to engage, respectively, with contact pins 15 and 16, each of such pins being set in a tubular bushing 17, and normally resiliently held in the position shown in Fig. 2 by means of a helical spring 18, arranged inside of the bushing. The bushings 17 are supported by, but insulated from, the frame members 2^a and 2^b, as clearly shown in Fig. 2.

By reference to Figs. 5 and 6, it will be observed that the contact screws 13 and 14 increase progressively in length from one end of the group to the other, while the

ends of each group of pins 15 and 16 are in alignment. From this it follows that as the bell crank moves one way or the other from the intermediate position shown in Fig. 2, the contact screws in either group will be brought successively into engagement, one after another, with the corresponding contact pins 15 or 16. In practice, the length of the contact screws of each group will differ by a very small amount, such, for example, as one one-hundredth of an inch, and by making the ratio between the short and long arms of the bell crank lever large, such, for example, as one to ten, it is evident that a movement of one one-thousandth of an inch of the roller 8 will serve to produce a sufficient movement of the head 12 to cause the engagement and disengagement of said screws and pins. It will also be noted that, inasmuch as the pins 16 are resiliently mounted, the first members of each group can yield easily so as to permit the last contact screw of the series to engage its pin.

25 Mounted adjacent each pair of rollers 7-8, is a series of recording devices which have been shown as in the nature of levers 19, pivoted at 20 and having one end bent slightly upward and brought to a fine point, as indicated at 21, to form a scribe. Each of these scribes or points is located preferably on a line joining the axes of the rollers 7 and 8.

30 Adjacent the rear ends 22 of the levers 19 are disposed magnets 23, 23', so arranged that when energized each magnet will serve to force the corresponding scribe 21 upward. As shown in Fig. 3, these magnets are preferably arranged in staggered relation for the sake of compactness. Four levers 19 and magnets 23 have been shown on one side of each pair of rollers, and similar levers 19' and magnets 23' have been shown on the other side of each pair of rollers, the number of levers and magnets in each group corresponding to the number of contact screws in each group 13-14.

35 A suitable source of current, such as a battery 24, is provided, and has one side connected with the frame of the machine, as by means of a wire 25. The other pole of such battery is connected by means of a wire 26 with one terminal of the winding of each magnet. One terminal of the winding of each of the magnets 23 is connected, as by means of a wire 27, with one of the contact pins 15, while the other terminal of the winding of each of the magnets 23' is connected with one of the pins 16, as by means of a wire 28. It will be also noted that the winding of the magnets for the two levers nearest to the rollers 7 and 8 are connected to the two pins 15 and 16, which are opposite the longest contact screws 13 and 14, and that the pins opposite the screws

of progressively decreasing length are connected to the windings of the magnets associated with the levers disposed at increased distances from the rollers. It therefore follows that, upon a movement of the bell crank lever in either direction, the scribes located nearest the rollers will be first actuated, and then those more remote, in succession.

40 The operation of the machine is simple. A sheet of mica, such as indicated by 29, is fed between the rollers 7 and 8, such rollers having been previously adjusted by means of the screws 3 to a distance apart just equal to the desired thickness of the finished sheet. It will be seen that, as the sheet moves through the machine, any variations in thickness will cause the rollers 8 to move up or down, and the bell crank levers to be correspondingly rocked. If, for example, a portion of the sheet of abnormal thickness should pass between the right hand pair of rollers 7 and 8, shown in Fig. 1, the corresponding bell crank would be rocked to the right as seen in Fig. 2, and the contact screws 14 would be brought into engagement with the contact pins 16. This would result in the energization of the magnets 23' of this group, and such magnets would pull down upon their corresponding levers 19' and force the scribes 21 up into contact with the under side of the sheet. In this connection it will be observed from what has already been stated that, if there is only a slight variation in the thickness of the sheet, only the first and longest of the contact screws of the group will engage its contact pin, and only the scribe nearest the rollers will be brought into operation. If, however, a greater thickness is encountered the bell crank lever will be rocked still farther and the second longest contact screw brought into engagement with its pin, thus bringing into operation the second scribe. It will be understood, therefore, that the number of scribes brought into engagement with the sheet at any particular point is proportional to the amount of variation in the thickness of the sheet at that point. The greater the thickness, the larger the number of scribes brought into engagement.

45 The same operation takes place in connection with the scribes on the left hand side of the pair of rollers, only in reverse order. That is to say, if a thin place is encountered by the roller 8, the bell crank is rocked to the left, as viewed in Fig. 2, with a result that the contact screws 13 are brought into engagement, one after another, with their corresponding pins 15, thus energizing one or more of the magnets 23, and bringing one or more of the scribes into engagement with the sheet.

50 Referring to Fig. 7, the lines 30 represent

the path of the pair of rollers 7 and 8 over the sheet, while reference characters 31 and 32 designate the record made upon such sheet by the scribes. Pursuant with the 5 above explanation, it will be readily understood that marks such as 32, occurring upon the left hand side of the lines 30, indicate that the sheet is too thin at this point, while marks such as 31, occurring on the right 10 hand side of the lines 30, indicate that the sheet is too thick at such point. Moreover, the number of marks in each group indicate the extent of the excessive thickness or thinness, as the case may be. Thus, each 15 sheet, after it passes through the machine, contains upon itself a complete record of its own defects, and after a little experience the operator can tell at a glance just how much the sheet requires to be built up or shaved 20 off at the points indicated by the marks.

What I claim is:

1. In a thickness gaging machine for sheet material, means for feeding a sheet through the machine, and means separate from the 25 said feeding means but electrically actuated thereby for automatically producing on the sheet local markings corresponding with local variations from a uniform thickness.

2. In a thickness gaging machine for sheet 30 material, a plurality of pairs of feed rollers adapted to receive the sheet between them and to move toward and from each other with variations in the thickness of the sheet, recording means disposed adjacent each pair 35 of rollers, and electrically operated means controlled by the relative bodily movement of the rollers for automatically bringing such recording means into action whenever that portion of the sheet between said rollers 40 is either above or below a given uniform thickness.

3. In a thickness gaging machine for sheet material, a pair of feed rollers adapted to receive the sheet between them, a scribe 45 mounted adjacent said rollers, and electrically operated automatic means responsive to movement of one of the said rollers caused by abnormal thickness of the sheet for bringing said scribe into engagement with the 50 sheet.

4. In a thickness gaging machine for sheet material, a pair of feed rollers adapted to receive the sheet between them, a scribe mounted adjacent each side of said rollers, 55 and automatic means responsive to movement of one of the said rollers caused by variations of said sheet above or below a given thickness for bringing one or the other of said scribes into engagement with said 60 sheet.

5. In a thickness gaging machine for sheet material, a pair of feed rollers adapted to receive the sheet between them, a series of 65 scribes mounted adjacent said rollers, and automatic means controlled by one of the

said rollers for bringing said scribes successively into engagement with said sheet, one after another, as that portion of the sheet between the rollers varies more and more from a given thickness.

70

6. In a thickness gaging machine for sheet material, a pair of feed rollers adapted to receive the sheet between them, a series of scribes mounted adjacent said rollers, and automatic means controlled by one of said 75 rollers and responsive to a slight variation in thickness of said sheet for bringing one of said scribes into engagement with the sheet, and responsive to a greater variation in thickness for bringing a plurality of said 80 scribes into engagement with the sheet.

7. In a thickness gaging machine for sheet material, means for feeding a sheet through the machine, a series of scribes disposed adjacent the path of travel of the sheet, individual electro-magnetic means for actuating said scribes to bring them into engagement with said sheet, and means controlled by the sheet for energizing progressively increasing numbers of such electro-magnetic 90 means according as the thickness of that part of the sheet adjacent said scribes increases or diminishes.

8. In a thickness gaging machine for sheet material, means for feeding a sheet through the machine, a series of scribes disposed adjacent the path of travel of the sheet, individual electro-magnetic means for actuating said scribes to bring them into engagement with said sheet, and means controlled 100 by the sheet for energizing a number of such electro-magnetic means proportional to the extent of variation in thickness of that part of the sheet adjacent said scribes.

9. In a thickness gaging machine for sheet material, means for feeding the sheet through the machine, a pair of scribes arranged adjacent the path of the sheet, a pivoted lever, a pair of electrical contacts between which 110 said lever is arranged to vibrate, means governed by said contacts for respectively moving said scribes into engagement with the sheet, said lever being movable, in response to variations in thickness of said sheet, into engagement with one or the other of said 115 contacts.

10. In a thickness gaging machine for sheet material, the combination with a main frame, a shaft journaled therein, a set of rollers fixed to said shaft, a second set of 120 corresponding rollers, a lever for carrying each of said second set of rollers, a frame on which said levers are pivotally mounted, recording devices, means whereby the said recording devices are controlled by the movement of said levers, and means for shifting the position of the lever frame relative to the main frame, whereby the distance between said sets of rollers may be adjusted.

11. In a thickness-gaging machine for 130

sheet material, means for feeding a sheet through the machine and for gaging the sheet, means for recording on the sheet itself any variations from a uniform thickness and means whereby such recording means is electrically controlled by the first-named means.

12. In a thickness-gaging machine for sheet material, a plurality of pairs of feed rollers adapted to receive the sheet between them, recording means disposed on each side of each pair of rollers and adapted for marking a record on the sheet, means controlled by relative bodily movement of such 15 pair of rollers for automatically bringing the recording means on one side or the other of such pair of rollers into action according as that portion of the sheet between said pair of rollers is either above or below a 20 given thickness.

13. In a thickness-gaging machine for sheet material, means for feeding a sheet through the machine and for gaging the sheet, a scribe located adjacent the path 25 of travel of the sheet and automatic means governed by relative bodily movement of the rollers, due to changes in thickness of the sheet, for causing the scribe to engage the sheet.

14. In a thickness-gaging machine for sheet material, means for feeding a sheet through the machine and for gaging the sheet, a scribe located adjacent the path of travel of the sheet, electromagnetic means 35 for actuating the scribe, and means governed by relative bodily movement of the rollers, due to changes in the thickness of the sheet, for controlling the circuit of such electromagnetic means.

15. In a thickness-gaging machine for sheet material, means for feeding a sheet through the machine and for gaging the sheet, a pair of scribes located adjacent the path of travel of the sheet, individual 45 electromagnetic means for actuating each of such scribes, means responsive to relative movement of the rollers, due to an increase in the thickness of the sheet, for closing the circuit of one electromagnetic means, and 50 means responsive to such movement, due to a decrease in the thickness of the sheet, for closing the circuit of the other electromagnetic means.

16. In a thickness-gaging machine for sheet material, means for feeding a sheet through the machine, such means comprising a power shaft mounted in fixed bearings, a roller secured to said shaft, a pivoted le-

ver, a second roller mounted on the lever and disposed opposite the first roller, said lever being adjustable toward and away from the shaft so as to vary the distance between said rollers in accordance with the average thickness of the sheet being gaged, a recording means adjacent said rollers controlled by the relative movements of the latter and responsive to variations in the thickness of the sheet.

17. In a thickness-gaging machine for sheet material, means for feeding a sheet through the machine and for gaging the sheet, a scribing device separate from the feeding means for recording on the sheet itself any variations from uniform thickness and means whereby such recording means is electrically controlled by the first-mentioned means.

18. In a thickness-gaging machine for sheet material, means for feeding a sheet through the machine, a mechanism movable 80 to inscribe on the sheet, electrically operated actuating means for such mechanism, and means controlled by the first-named means for rendering the said actuating means active upon changes in thickness of the sheet.

19. In a thickness-gaging machine for sheet material, means for feeding a sheet through the machine, a plurality of independent means for marking the sheet, electrical means including circuits each rendering active one of the marking means, and means controlled by movement of the feeding means, due to changes in thickness of the sheet, for selectively closing the circuits.

20. In a thickness-gaging machine for sheet material, means for feeding a sheet through the machine, a plurality of independent means for marking the sheet, electrical means including circuits each rendering active one of the marking means, and means controlled by movement of the feeding means, due to changes in thickness of the sheet, for selectively closing the circuits, one circuit being closed, due to increase in thickness of the sheet and another circuit being closed, due to decrease in thickness of the sheet.

In testimony whereof, I have hereunto subscribed my name this 29th day of Nov. 110 1913.

HENRY R. EDGEcomb
